UNITED STATES PATENT OFFICE

2,545,565

LINE CLAMP

Milbert D. Bible, Mosheim, Tenn.

Application October 2, 1947, Serial No. 777,458

2 Claims. (Cl. 24—136)

1

The present invention relates to new and useful improvements in line clamps for holding a line at any point intermediate its ends and more particularly to means for securing a clothes line in adjusted position in a clothes line frame of the type disclosed in my prior Patent No. 2,337,175, dated December 21, 1943.

An important object of the present invention is to provide a line clamp for securely holding the line by a wedging action and without the danger of cutting or injuring the line by the clamping member.

A further object of the invention is to provide a clothes line clamp of this character having a double wedging action with respect to the line whereby the line will be securely held at two points.

A still further object is to provide a device of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing a clothes line support equipped with the line clamp;

Figure 2 is an enlarged fragmentary sectional view taken substantially on the line 2—2 of Figure 1;

Figures 3 and 4 are transverse sectional views through the clamp taken respectively on the lines 3—3 and 4—4 of Figure 2.

Referring now to the drawing in detail wherein for the purpose of illustration I have disclosed a preferred embodiment of the invention the numerals 5 and 6 designate a pair of rigid bars secured in a horizontal position in spaced parallel relation with respect to each other to posts 7 and 8 by a clothes line 9 which extends through openings 10 in the bars in the manner as disclosed in my aforesaid patent to stretch the line in parallel flights as shown at 11 between the bars 5 and 6.

The line 9 is passed back and forth adjacent parallel openings 10 as indicated in Figure 4, a part of the line being loose and looped as shown at 12 to provide for an adjustment of the line in accordance with the distance at which the bars 5 and 6 are placed with respect to each other.

In order to hold the flights 11 of the line taut

2

I provide a line clamp designated generally at 13 and comprising a pair of channel-shaped clamping members 14 positioned in the opposite ends of a tapered slot 15 extending vertically through the bar 5 and transversely with respect to the rounded vertical edge of the clamping members 14 may be moved into and out of gripping engagement with the line.

The upper and lower edges of the clamping members 14 are formed with outwardly rolled flanges 16 to engage respectively the upper and lower surfaces of the bar 5 to hold the clamping members against vertical movement in the slot 15.

15 A tapered wedge 17 of flat construction is inserted in the slot 15 with its vertical edges received in the channels of the clamping members 14. The upper and lower edges of the wedge 17 are rolled as shown at 18 to provide finger grips for manipulating the wedge.

In the use of the invention the channel-shaped clamping members 14 are placed in the slot 15 as illustrated in Figures 2, 3 and 4 to bear against the rope 11 in a pair of the openings 10 extending through the cross bar. The forcing of the wedge 17 down in the channels of the clamping members 14 will spread the latter apart and thus provide a double gripping action on the line to thus hold the line against slipping.

20 The upper and lower flanges 16 on the clamping members 14 hold the same in the slot 15 when the wedge 17 is loosened or removed and the channel-shaped construction of the clamping members 14 with their rounded edges bearing against the rope eliminates any possibility of the cutting of the rope.

25 In view of the foregoing description taken in conjunction with the accompanying drawing it is believed that a clear understanding of the construction, operation and advantages of the device will be quite apparent to those skilled in this art. A more detailed description is accordingly deemed unnecessary.

30 It is to be understood, however, that even though there is herein shown and described a preferred embodiment of the invention the same is susceptible to certain changes fully comprehended by the spirit of the invention as herein described and the scope of the appended claims.

35 Having described the invention, what is claimed as new is:

40 1. In a line clamp, a body having a slot extending entirely through the body, said body also having openings passing through the body at right angles to the slot and intersecting the slot

45

at the ends thereof to partially expose a line in the slot when placed in either or both of said openings, a wedge inserted in the slot, and a pair of channel shaped separators in the slot and in which the side edges of the wedge are received to clamp the line in its opening.

2. In a line clamp, a body having a slot extending entirely through the body, said body also having openings passing through the body at right angles to the slot and intersecting the slot at the ends thereof to partially expose a line in the slot when placed in either or both of said openings, a wedge inserted in the slot, and a pair of channel-shaped separators in the slot and in which the side edges of the wedge are received to clamp the line in its opening, said separators having a rounded web portion contacting the line.
